TRACTOR MOUNTED DIGGER

Eli R. Lupin, Royal Oak, Mich.

Application October 16, 1957, Serial No. 48,121

Term of patent 14 years

(Cl. D14—3)

Fig. 1 is a side elevational view of a tractor mounted digger shown mounted on a tractor;

Fig. 2 is a perspective view; and

Fig. 3 is a plan view.

The portions of the tractor shown in broken lines are for purposes of illustration only.

I claim:

The ornamental design for a tractor mounted digger, as shown and described.
